UNITED STATES PATENT OFFICE.

ROBERT A. BRINKLEY, OF WOODLAWN, NORTH CAROLINA.

DESIGN FOR A PACK OF GAME-CARDS.

48,810.

Specification for Design.

Patented Apr. 4, 1916.

Application filed August 22, 1914. Serial No. 858,122. Term of patent 14 years.

To all whom it may concern:

Be it known that I, ROBERT A. BRINKLEY, a citizen of the United States, residing at Woodlawn, in the county of McDowell and State of North Carolina, have invented a new, original, and ornamental Design for a Pack of Game-Cards, of which the following is a specification, reference being had to the accompanying drawings, forming part thereof.

The drawings show the various cards, contained in the pack and illustrating my new design.

I claim:

The ornamental design for a pack of game cards as shown.

ROBERT A. BRINKLEY.

Witnesses:

C. A. McCALL,
W.M. McCALL.
